JOSEPH F. MORAN, OF WATERBURY, CONNECTICUT, ASSIGNOR TO SCOVILL MANUFACTURING COMPANY, OF WATERBURY, CONNECTICUT, A CORPORATION OF CONNECTICUT

FLASH LIGHT

Application filed August 12, 1930. Serial No. 474,736.

The invention relates to a flash light and in particular to one which is so designed that it may be carried in a pocket like a fountain pen or pencil. Heretofore, flashlights of this type have been so constructed as to provide either for flashing operation only of the associated lamp, or for permanent lighting only. In the former type, it was necessary to manually hold the circuit-controlling mechanism in circuit-closing position in order to light the lamp, with the result that the device could not be laid down or released without extinguishing the lamp. With the second type, it was necessary to place the current-controlling mechanism in permanent lighting position in order to operate the lamp, the current-controlling mechanism being such as to produce either a constant light or no light at all. An object of this invention is to provide a pocket flashlight of the so-called pencil type constructed and arranged to permit the selective flashing or permanent lighting of the lamp.

A feature of the invention is the simplicity of construction, assembly, and operation of my light. I am aware that flash lights of this type, generally known as "pencil flash lights" have been well known for some years past, but the construction of such lights is generally quite complicated, their disassembly to remove a worn-out bulb or battery and reassembly after insertion of the fresh part, is correspondingly intricate and annoying, and the operations required for closing the light circuit, while relatively simple, occupy an unnecessary amount of time and cause unnecessary annoyance to the user. I propose by my invention to simplify all of these operations and provide a light of the type hereinafter to be explained which will serve its purpose as satisfactorily as those at present in use and which will be simple and inexpensive in construction and easily and conveniently operated.

In the drawing:

Figure 1 is a view, partly in elevation and partly in section, of the assembled light, in non-operative or open circuit position.

Figure 2 is a view of the inside of the cap 50 or top covering of the light.

Figure 3 is a view in elevation of the top covering and of the top portion of the light, over which it fits.

For the purpose of my invention I provide 55 a relatively long, metallic shell 1, which may, and preferably does, have the general configuration of a fountain pen. This shell is provided on its outer portion with a clip 2 for attachment to a pocket edge. The clip 60 may be attached to the shell in any suitable manner. The lower end of this shell 1 is turned inwardly at 3 to provide an annular groove or channel in which the edge of the protecting collar 4 of the lamp 5 may rest. 65 A sleeve 6 which may be of rubber or some similar resilient material is provided, which is adapted to fit around the threaded portion of the lamp-bulb and to hold the terminal 7 thereof normally out of engagement with 70 the positive electrode 8 of the battery 9.

The top of the cap 10 is preferably made concave in the center, as at 11, to provide on the underside thereof a point 12 which is at all times in contact with the negative electrode of the battery 9. Inner projections 13, 13 formed by pressing in the sides of the cap, as at 14, 14, are adapted to fit into the angular slots 15, 15 and to ride therein, whereby the cap is secured in one or more operative 75 positions on the shell, and the electric circuit thus regulated. An elongated vertical slip 16 cut in the top of the shell 1, by imparting a resilient character to the metal of the shell surrounding it, enables the user easily to slip the cap over the top of the shell 1 by direct pressure.

The operation and assembly of the light will be readily understood. In assembling the light, the lamp-bulb 5 is first screwed into 80

the threaded portion 4a of the collar 4, and the sleeve 6 preferably fitted in position over the collar 4. Collar, lamp and sleeve, preferably though not necessarily thus fully assembled, are then dropped into the metallic shell 1 from the end opposite the flanged end and automatically place themselves so that the edge of the collar seats in the channel formed by the flange. Dropping in the battery and slipping the cap over the open end completes the assembly.

When the light is not being operated the projections 13, 13 on the inner sides of the cap 10 are at the uppermost points 17, 17 of the slots 15, 15 as shown in Figure 1. For intermittent flashing it is only necessary to apply slight pressure to the top of the cap, whereby the projections 13, 13 ride freely downwards in the vertical portion of the slots and the battery is pushed down, compressing the sleeve 6 until the battery electrode 8 meets the terminal 7 of the light and closes the circuit. Intermittent lighting may also be realized by pressing lightly with the thumb or finger on the bulb 5, thus compressing the sleeve 6 and bringing the terminal 7 into contact with the electrode 8. Permanent contact is made by screwing the cap slightly to the right whereby the projections 13, 13 ride freely in the angular portion of the slots 15, 15 to the points 18, 18 where they are frictionally held and thus hold the sleeve 6 permanently compressed and the terminals 7 and 8 in permanent contact one with another.

It will be apparent that the circuit controlling cap can be manipulated to permit either intermittent flashing of the lamp or to provide a constant light. Longitudinal movement of the cap along the casing, in which the projections 14 move along the longitudinally extending portions of the slots 15, permits intermittent flashing, while rotation of the cap on the casing in which the projections 14 move down the inclined portions 18 of the slots draws the cap inwardly to close the circuit terminal, the friction between the projections 14 and the edges of the slot portions 18 being sufficient to hold the cap in circuit closing position against pressure of the spring sleeve 6. As a result, the flashlight will produce a constant light when desired so that it can be laid down without extinguishing the lamp. The two movements of the cap are selective and can be instantly made by the operator to obtain either effect desired.

It is to be understood that the invention may be variously modified and embodied within the scope of the subjoined claim.

60 I claim:

A pencil type vest pocket flashlight having in combination a lamp, a battery, a metallic casing forming part of the electric circuit between said lamp and battery, said battery being longitudinally movable relatively to said

casing for closing said circuit, means for yieldingly pressing said battery to open said circuit, an end cap movably mounted on said casing and electrically connected with one terminal of said battery, a projection on said cap slidably positioned in a slot formed in said casing, said slot having a longitudinally extending portion and an angularly extending portion, to permit selective longitudinal movement of said cap for flashing, or rotation of said cap for constant lighting.

In testimony whereof, I have signed my name to this specification this 7th day of Aug., 1930.

JOSEPH F. MORAN.
